PACKING SHEET

Charles J. Chaplin, South Portland, Maine, assignor to Chaplin Corporation, South Portland, Maine, a corporation of Maine

Application May 1, 1951, Serial No. 15,028

Term of patent 14 years

(Cl. D58—13)

To all whom it may concern:

Be it known that I, Charles J. Chaplin, a citizen of the United States of America, residing at South Portland, in the county of Cumberland and State of Maine, have invented a new, original, and ornamental Design for a Packing Sheet, of which the following is a specification, reference being had to the accompanying drawing, forming part thereof.

In the drawing:

Fig. 1 is a top perspective view of a packing sheet showing my new design.

Fig. 2 is a bottom perspective thereof.

Fig. 3 is a section on the line 3—3 of Fig. 1.

I claim:

The ornamental design for a packing sheet, as shown.

CHARLES J. CHAPLIN.
